UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

POST.

Application filed June 27, 1925. Serial No. 40,024.

My invention relates to posts constructed for location in the ground and serving as supports, attaching means, anchors, etc. The post of my invention employs a bar formed with side walls which are collapsed at the lower end of the bar, and an anchoring body moulded about said bar where collapsed. The side walls of the bar, where collapsed, cooperate with each other to prevent the withdrawal of the bar from the anchoring element.

In the preferred embodiment of the invention the bar is in the form of an angle iron whose sides or walls, where collapsed, are shaped into intermeshing, sinuous formations. The sinuous formations in the walls or sides of the angle iron prevent the angle iron from being withdrawn from the moulded anchoring element, the walls engaging each other to prevent them from being movable toward each other by the action of the surrounding moulded material, which is preferably concrete, when the bar is stressed.

The invention will be more fully explained in connection with the accompanying drawing in which Fig. 1 illustrates the preferred embodiment thereof as employed in connection with a tower formed of structural iron, such as used, for example, in supporting wind mills and high tension current transmission wires; Fig. 2 is a longitudinal sectional view showing the angle iron of the post in elevation, the concrete being removed from the space between the side walls of the angle iron, for clearance; Fig. 3 is a perspective view illustrating the collapsed formation of the angle iron, the upper portion of the angle iron being broken away; Fig. 4 is a view of the lower portion of the structure shown in Fig. 2 on line 4—4 of Fig. 2; and Fig. 5 is a sectional view on line 5—5 of Fig. 2.

The tower structure shown in Fig. 1 has as many underlying posts as it has sides, each inclined corner rail 1 of the tower being riveted at its lower or ground end with the upper end of a bar which, as illustrated, is inclusive of two angularly related side walls 2 to constitute an angle iron. Each angle iron has its sides or walls 3 collapsed together at the lower end of the angle iron, the collapsed portions of the angle iron sides

or walls 2 being shaped into intermeshing formations 3. The angle irons are inserted in suitably prepared holes in the ground, whereafter concrete is poured into the holes in the ground to surround the angle irons therein, particularly the portions of the angle irons where their sides are collapsed. The body of concrete surrounding the collapsed portion of each angle iron is enlarged at the lower end of the post into a ball 4, the concrete body being reduced above the ball 4 to form a stem 5 that surrounds the upper parts of the collapsed portions of the angle iron and also the uncollapsed balance of the angle iron. The enlargement 4 serves to prevent the withdrawal of the post, as a whole, from the ground. The sinuous formations 3, by engaging each other, are prevented from coming any closer together so that the angle iron cannot readily be withdrawn from the anchoring element surrounding it.

The corner rails 1 of the tower are desirably of angle iron with the corners outermost. Consequently the corners of the angle irons in the posts are outermost, these angle irons and the inclined corner rails 1 of the tower being in nesting engagement. With this construction the channels in the angle irons face downwardly somewhat, and therefore cannot serve to conduct the concrete as this concrete is inserted in the post holes. The concrete should be packed, however, into the holes in a manner to fill the channels in the angle irons as compactly as possible. If the concrete could be as tightly packed into the channels in the angle iron as desirable in the construction of the various posts, the walls of the angle irons might be prevented from collapsing by the concrete interposed therebetween. As this result cannot, however, be assured, I have resorted to the collapsing of the angle iron sides as set forth, whereby these sides reinforce each other and prevent their further collapsing to guard against the withdrawal of the angle irons from the concrete anchoring elements. In actual practice the post holes are formed by means of earth augers, these holes being enlarged at their lower ends by explosion in a manner well known, the ground where the post holes are thus formed acting as a mould in which the angle irons are inserted.

to serve as cores in the mould and about which cores the concrete is poured and packed.

Having thus described my invention, I claim:

1. A ground anchorage for a tower or similar structure comprising a length of angle iron adapted to be inserted in a hole in the ground, the upper end portion of said angle iron being adapted for connection with the tower or similar structure and being of normal configuration with the side walls thereof disposed at or substantially at right angles to one another to resist bending strains imposed thereon by the tower, the lower end portion of said angle iron having the side walls thereof collapsed together, and a mass of cementitious material surrounding the collapsed lower end portion of said angle iron.

2. A ground anchorage for a tower or similar structure comprising a length of angle iron adapted to be inserted in a hole in the ground, the upper end portion of said angle iron being adapted for connection with the tower or similar structure and being of normal configuration with the side walls thereof disposed at or substantially at right angles to one another to resist bending strains imposed thereon by the tower, the lower end portion of said angle iron having the side walls thereof collapsed together, and a mass of cementitious material surrounding the collapsed lower end portion

of said angle iron, the said collapsed side walls of the lower end portion of said angle iron being provided with intermeshing sinuous formations.

3. A ground anchorage for a tower or similar structure comprising a length of angle iron adapted to be inserted in a hole in the ground, the upper end portion of said angle iron being adapted for connection with the tower or similar structure and being of normal configuration with the side walls thereof disposed at or substantially at right angles to one another to resist bending strains imposed thereon by the tower, the lower end portion of said angle iron having the side walls thereof collapsed together, lateral projections on the collapsed lower end portion of said angle iron, and a mass of cementitious material surrounding the collapsed lower end portion of said angle iron.

4. A post including a bar formed with side walls which are collapsed together at the lower end of the bar and shaped where collapsed into intermeshing sinuous formations, and an anchoring body moulded about said bar where collapsed and uncollapsed, this anchoring body being enlarged where it surrounds the collapsed portion of the bar.

In witness whereof, I hereunto subscribe my name.

DANIEL R. SCHOLES.
